ELECTRICAL SWITCH GEAR

Filed Sept. 4, 1930

Frederick J. Keeley Inventor.
M. H. Lockwood Attorney.

UNITED STATES PATENT OFFICE

FREDERICK JOSEPH KEELEY, OF STREETLY, ENGLAND, ASSIGNOR TO THE GENERAL ELECTRIC COMPANY LIMITED, OF LONDON, ENGLAND

ELECTRICAL SWITCH GEAR

Application filed September 4, 1930, Serial No. 479,596, and in Great Britain September 12, 1929.

This invention relates to electric power apparatus of the drop down type and is particularly useful in connection with switches although it may find application in connection with other units of apparatus which are arranged to be withdrawn.

One object of the invention is to facilitate the removal and replacement of a member of apparatus by the provision of an arrangement whereby accurate positioning of the member beneath the sockets or equivalent coupling devices before raising the member into its operative position is attained quickly and without difficulty.

25 A further object is to provide apparatus in which the material of which it is constructed can be economically utilized without unduly stressing any parts of the apparatus.

In general the object of the invention is to 20 provide improved raising and lowering gear.

Other and further objects and advantages of the present invention will be apparent from the following description of a preferred embodiment thereof, reference being made 25 to the accompanying partly diagrammatic drawing which shows a front elevation of an oil filled metal clad switch unit in its operative position relatively to a set of busbars, together with raising, lowering and supporting 30 gear therefor.

In the drawing the busbar chamber 1 is supported on four uprights 2 a couple of which only are seen in the figure, there being a further pair of uprights behind those 35 shown. The three phase switch unit comprises the usual tank 3 and cover 4, the latter supporting the three insulators 5 of the different phases, two only of which are seen in the drawing, the upper parts of which insulators enter the insulating sleeves 6 in order that the plugs shall respectively engage the sockets severally connected to the different busbars. Behind the insulators 5 are three 40 corresponding insulators also supported by the cover and arranged with plugs for engaging sockets associated with the line side of the switch.

The tank 3 and the switch parts directly 45 associated therewith are supported from brackets 7 projecting inwardly from the up-

rights 2 by members including short shafts 8 rotatably mounted in thrust bearings provided in the brackets 7 and adapted to take the downward pull of the parts supported thereby. On the upper end of each shaft 8 55 is mounted a bevel wheel 9 which meshes with another bevel wheel 10. The foremost and hinder bevel wheels 10 at the left hand of the figure are secured to a shaft 12 rotatably mounted in suitable bearings, whilst similarly the foremost and hinder bevel wheels 10 at the right hand of the figure are secured to a rotatably mounted shaft 11. The shafts 11 and 12 are geared together in any suitable manner, for example, by means of a shaft 13 60 rotatably mounted in bearings 14 and provided at its ends with bevel wheels 15 respectively engaging further bevel wheels severally secured to the far ends of the shafts 11 and 12, the arrangement being such that rotation 65 of the shafts 11, 12 and 13 results in rotation of the four shafts 8 in the same sense and at equal rates. Any suitable means, for example, an electric motor may be provided for turning the shafts, or the shaft 11 may be 70 extended slightly forward and provided with the projecting pins 16 for engaging corresponding slots in the head of a handle 17 (shown in dotted lines) arranged to fit on the end of the said shaft, the handle then serving 75 to operate the gear.

The tank 3 is formed with sidewardly extending supports 18 having on their under surfaces slots 19 into which fit ribs 20 diametrically arranged on the upper surfaces of 80 internally threaded sleeves 21. Passing through the respective sleeves 21 and through recesses in the supports 18 are four spindles 22 having similar screw threads which cooperate with the internal threads of the sleeves. The four spindles 22 are respectively connected to the four shafts 8 through universal couplings 24.

The universal couplings may of course be of any suitable construction, but in the form shown each coupling includes a block 25 from opposite sides of which extends a pair of pins 26 and from the other sides of which and at right angles to the pins 26 extend in a similar manner a pair of pins 27. The pins 26 fit and 85

are adapted to rotate within holes formed in opposite limbs 28 of an inverted U-shaped member that embrace the block 25. The associated shaft 8 near its lower end is of reduced 5 diameter so that a head 32 is formed and the limbs 28 are separate from one another and engage the shaft 8 above the head 32 at the part of reduced diameter to which they are rigidly clamped by nuts and bolts or the like

10 29. Similarly the pins 27 fit and are adapted to rotate within holes formed in opposite limbs 34 of a U-shaped member which also embrace the block 25, whilst the associated spindle 22 near its upper end is of reduced 15 diameter so that a head 33 is formed and the limbs 34 are separate from one another and engage the spindle 22 below the head 33 at the part of reduced diameter, to which they are rigidly clamped by nuts and bolts or the like

20 31. Since the supports 18 rest directly on top of the sleeves 21 the force on the spindles 22 due to the weight of the tank 3 and the switch parts directly associated therewith is simply 25 one of tension, there being no bending moment as in the case of a sleeve or nut with a side- 30 wardly extending lug for supporting the moving switch parts.

In operation by rotating the shafts 11 and 30 12 in the appropriate direction the sleeves 21 descend on the spindles 22 and the tank 3, the cover 4 and the switch are lowered. Generally means will be provided as is usual for supporting the cover 4 and the switch after 35 the latter has become isolated by disengagement and separation of the switch plugs from the busbar sockets so that further lowering of the tank exposes the switch contacts. When the tank 3 has been fully lowered a 40 small additional rotation of the spindles 22 causes a further lowering of the sleeves 21 whereupon the tank 3 together with the switch itself if the latter has also been fully lowered may be moved away on its transport carriage 45 or wheels.

When a tank is moved into place beneath the busbar chamber 1 it is unnecessary to position the tank with accuracy since, provided the tank is approximately in position, the 50 spindles 22 may be rotated about the universal couplings 24 and the sleeves 21 thereby swung beneath the supports 18 with the ribs 20 registering with the slots 19. When then the spindles 22 are rotated to raise the sleeves 21 55 and the tank 3, the latter, being suspended on the spindles from the universal joints 24, is automatically and correctly centered and continued rotation of the spindles causes the tank and switch to rise with the switch plugs 60 immediately beneath the busbar sockets until the switch is in its operative position. It will be seen that the mechanical power is transmitted along the longitudinal axes of the spindles 22.

65 If desired means may be provided for pre-

venting rotation of the sleeves 21 on the spindles 22 when the ribs 20 are not in engagement with the slots 19. For example, sidewardly projecting pins may be provided near the lower ends of the spindles 22, the sleeves 21 at their lower extremities being formed with corresponding longitudinal slots or grooves that engage with the pins when the ribs 20 commence to move out of the slots 19.

I claim:

1. Electrical switchgear comprising a supporting frame, a withdrawable switch and tank member, complementary electrical coupling devices on the supporting frame and said withdrawable member, a plurality of screws for raising and lowering said withdrawable member, said screws being suspended from the supporting frame by universal joints and separable engaging means between the withdrawable member and said screws adapted with the cooperation of said universal joint for the automatic alignment of said tank and the switch coupling devices during operation of the screws in restoring these parts to normal operative position.

2. Electrical switchgear comprising, a supporting frame, a withdrawable switch and tank member, separable switch coupling devices on the supporting frame and said withdrawable member, a plurality of simultaneously rotatable screws for raising and lowering said withdrawable member, said screws being suspended from the supporting frame by universal joints, brackets engaging nuts on the screws for suspending said withdrawable member and engaging elements between said brackets and nuts adapted in cooperation with said universal joints for automatically positioning said withdrawable member for alignment of said tank and switch coupling devices.

FREDERICK JOSEPH KEELEY.
